FOREIGN PATENT DOCUMENTS

FR 2327727 5/1977

Primary Examiner—Catherine R. Oliver*(74) Attorney, Agent, or Firm*—Boyle, Fredrickson, Newholm, Stein & Gratz, S.C.**CLAIM**

The ornamental design for the body of a frog-shaped fishing lure, as shown and described.

DESCRIPTION

FIG. 1 is an isometric view of a frog-shaped lure body incorporating my new design, wherein the dashed lines form no part of the claimed design;

FIG. 2 is a top plan view thereof;

FIG. 3 is a left side elevation thereof, the right side elevation view being a mirror image;

FIG. 4 is a bottom plan view thereof;

FIG. 5 is a front elevation view thereof;

FIG. 6 is a rear elevation view thereof; and,

FIG. 7 is a bottom plan view of a frog-shaped fishing lure as shown in FIGS. 1-6, wherein a central portion is illustrated in phantom and forms no part of the claimed design.
